UNITED STATES PATENT OFFICE.

FRANÇOIS ISIDORE LAVÉRAN, OF TOULOUSE, FRANCE.

NECKTIE HOLDER.

Application filed June 4, 1919. Serial No. 361,768.

To all whom it may concern:

Be it known that I, FRANÇOIS ISIDORE LAVÉRAN, a citizen of the Republic of France, residing at Toulouse, 11 Rue Caffarelli, France, manufacturer, have invented new and useful Improvements in Necktie Holders, of which the following is a specification.

My invention relates to a double toothed rack apparatus intended for directly securing to the shirt collar or collar, at a height which can be varied with the utmost ease, neckties, bows or other similar pieces of clothing.

15 Said apparatus allows:

1. To place the neck-tie at the desired height, without fearing to crease the collar, by means of a slight upward push;

20 2. To hold said neck-tie securely fixed to the shirt collar's or collar's button, thus avoiding all displacement and deviation together with the resulting unsightly effect, to conceal the collar's button;

3. To withdraw the neck-tie with the utmost ease through a simple downward pull;

The annexed drawing shows by way of example a practical form of the apparatus constructed according to my invention:

Fig. 1 is a front view of the neck-tie holder of which Figs. 2 and 3 show the separate parts;

Fig. 4 is a perspective view;

Fig. 5 shows a special model for bows and

35 Fig. 6 shows the apparatus adapted for holding a neck-tie with resilient wings.

The apparatus is essentially formed with a double toothed rack *a* of which the notches are held brought together by means of a spring secured at *b* in front of an U shaped slot *d* intended to admit the stem of the collar's button. The frame *c*, which may be made of metal, horn, celluloid or other suitable material, is provided with extensions *e* enabling the neck-tie holder to be secured 45 at the proper place on the neck-tie.

When the spring-toothed rack *a* is adapted to the holder of a neck-tie with resilient wings, the stem of said holder may have a round window *f* for passage of the head 50 of the collar's button. The resiliency of the wings completing the action of the rack, enables said holder to exactly and auto-

matically adapt itself to all forms of down folded collars and the neck-tie to reach the maximum height it can.

55 The neck-tie holder so described works as follows:

The apparatus being secured to the neck-tie or to the neck-tie support, engages the button's head through the window *f* and its stem in the slot *d*, push then slightly upward up to the chosen notch; the spring-rack *a* then holds the neck-tie hung to the button; in order to withdraw said neck-tie, all that is necessary is to slightly pull down; the two legs of the spring-rack will open allowing the button's stem to pass freely and the neck-tie becomes disengaged.

The idea of the double toothed rack the notches of which are held together by a spring and between which an axis can, under the action of a push or of a pull, take at will different positions, could receive all other applications it may be able to give.

What I claim is:

1. A necktie holder comprising a supporting member for attachment to a tie and having a slot open at one end to clear the head and corresponding in width with the diameter of the shank of a collar button to receive said shank, and a spring on one side of said member and having terminal arms attached thereto and also having an intermediate U-shaped portion the sides of which have racks arranged parallel with and at opposite sides of said slot, to receive and yieldably hold the collar button shank in any of their notches.

2. A necktie holder comprising a supporting member for attachment to a tie and having a slot open at one end to clear the head and corresponding in width with the diameter of the shank of a collar button to receive said shank, and a spring-pressed rack on said support, arranged at one side of said slot and also arranged to receive and yieldably hold the collar button shank in any of its notches.

In testimony whereof I affix my signature in presence of two witnesses.

FRANÇOIS ISIDORE LAVÉRAN.

Witnesses:

JAMES D. CHILD,
JOHN W. TAIT.
